(57) CLAIM

The ornamental design for a bento box, as shown and described.

DESCRIPTION

FIG. 1 is a top, front, right side perspective view of a bento box, showing my new design;

FIG. 2 is a bottom, rear, right side perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is an enlarged view of detail 9 in FIG. 4.

The dashed broken lines in the drawings depict portions of the bento box that form no part of the claimed design.

The dash-dot broken lines in the drawings depict the boundaries of the claim and form no part thereof.

The long dash-short dash-short dash broken lines depict the boundaries of the enlargements and form no part of the claimed design.

1 Claim, 9 Drawing Sheets
